UNITED STATES PATENT OFFICE.

GODFREY DAWE, OF EAU CLAIRE, WISCONSIN.

MEANS OF KEYING WHEELS, PULLEYS, &c., TO SHAFTING.

SPECIFICATION forming part of Letters Patent No. 296,317, dated April 8, 1884.

Application filed February 28, 1884. (No model.)

To all whom it may concern:

Be it known that I, GODFREY DAWE, a citizen of the United States, residing in the city and county of Eau Claire, and State of Wisconsin, have invented a new and Improved Means for Keying Pulleys, Wheels, and the like to Shafting, of which the following, in connection with the accompanying drawings, is a specification.

10 This invention relates to a taper key with sharp longitudinal edges and an intermediate inner or under face, constructed in form of a part of a circle whose radius is less than the radius of the shaft to which the key is to be applied; and the object of the same is to insure the firm keying of pulleys, wheels, eccentrics, or cams, and the like, to shafting without the necessity of providing a key-seat on the shaft; and this object I attain by adopting the 15 aforesaid concave sharp-edged key, which enters into or takes a sufficient hold upon the metal of the shaft on opposite sides of the center thereof, when driven up tight into the usual tapered key-seat of the hub of the pulley or 20 wheel, to prevent the pulley or wheel turning on the shaft.

In the accompanying drawings, Figure 1 is a transverse section through the hub of a pulley, a shaft, and the improved keying device; 25 Fig. 2, a perspective view, on a larger scale, of the key; and Fig. 3 is a broken vertical longitudinal section of the shaft, pulley, and key shown in Fig. 1.

A in the drawings may designate a pulley, 30 wheel, eccentric, cam, or other part of machinery attachable by key B to shafting. This pulley is provided in its eye or bore with an inclined key seat or groove, *a*, which is cut into the metal of the hub from end to end, as 35 usual, or as shown in the drawings.

C is a shaft, made cylindrical along that portion where the pulley A is keyed to it—that is, it is turned or finished without cutting away or making a key-seat in it, thereby avoiding a 40 great amount of the time and expense required when such key-seat is provided, and also saving the shaft from being weakened by the cutting of it down to form such key-seat. Further, the shaft being constructed without a key-seat 45 and not requiring one, a pulley or wheel or other analogous part of machinery can instantly be applied to it, and as no key-seat is

ever required upon the shaft a great deal of time in laying out shafting is saved, and all parts of the shaft being turned cylindrical, 55 bearings, pulleys, or wheels can be attached at any desired place longitudinally of the shaft.

The shape of the key B is similar in many respects to the key in ordinary use, except on its under side, or the part which bears upon 60 the shaft, it is constructed with two parallel sharp cutting edges or ridges, *b b*, extending the full length of the key. These sharp edges are formed by constructing the under intermediate surface *c* of the key with a concave 65 form, the segment of the circle of which concave surface is struck from the center of a circle having a smaller radius than the radius of the circle of the shaft C, as illustrated in Fig. 1, and the sides of the key outside this concave surface being tapered downward on an angle sufficient to form, with the termini of the concave, a cutting-edge, *b*, on each side, said cutting-edges being as near as possible to the vertical sides of the key, or only slightly 70 overhung by the same. The key also has a taper, as usual, of one-eighth of one inch to every three inches of its length, corresponding to the incline *a* of the hub of the pulley.

By means of the taper form of the key and 75 the sharp cutting-edges *b b* a firm hold of the key upon the shaft is secured, for as the key is driven "home" in its seat *a* in the hub of the pulley the key is forced inward, and its cutting edges or ridges gradually cut two very 80 slight parallel channels into the surface of the shaft, and thus any turning of the pulley on the shaft will be impossible.

The key does not require to be driven 85 home as hard as the common square tapered key in a seat.

I am aware that it is not new to fasten or key a pulley or other part of machinery upon a shaft by means of the frictional bind of a concentrically-curved surface upon the shaft, 90 the binding force being produced by the combined action of a bolt and two reversely-inclined key-pieces; but this construction differs widely from my simple invention of a tapered key with sharp edges or ridges separated by a circular surface in relief from the shaft to which the key is applied.

What I claim as my invention, and desire to secure by Letters Patent, is—

1. A key for fastening a pulley, wheel, cam, eccentric, or other analogous part of machinery to shafting, consisting of a tapered bar having parallel sharp ridges or edges separated by a concave surface in relief from the shaft, substantially as and for the purpose described.

2. The combination, with a hub provided with a tapered key-seat, *a*, of a tapered key provided with parallel sharp ridges or edges separated by a concave surface in relief from

the shaft to which the hub is to be keyed, substantially as and for the purpose described.

3. The key having its edges beveled downward and its under surface made with the concave *c*, substantially as and for the purpose described.

GODFREY DAWE.
